UNITED STATES PATENT OFFICE.

THEODORE P. CORCORAN, OF FULLERTON, CALIFORNIA.

ORDERING CHART.

Application filed February 23, 1928. Serial No. 256,365.

This invention relates to new and useful improvements in charts whereby commodities delivered at the door, especially creamery products may be properly ordered so that 5 there will be no mistake on the part of the deliverer in leaving the required item.

The chart is primarily adapted for use in ordering creamery products such as milk, cream, butter, eggs or the like and aims to 10 provide a chart consisting of a plurality of pivotally interconnected cards having various orders marked thereon, the chart being of relatively narrow width so that the entire 15 chart, with the exception of the particular order card may be inserted within the neck of a bottle, the particular card protruding therefrom so that the deliverer may ascertain the exact item desired.

An important object of this invention is to 20 provide a chart of this character which is extremely simple of construction and inexpensive of manufacture so as to permit the creamery companies to dispense the same without charge to their customers.

25 In the drawing wherein like reference characters indicate corresponding parts throughout the several views:

Figure 1 is an elevation of my improved ordering chart, one of the designating parts 30 being partially swung out of normal position.

Figure 2 is a detail longitudinal section through the chart, and

Figure 3 is an elevation of a milk bottle 35 within which has been arranged an ordering chart, one of the particular cards having been swung to a position longitudinally of the chart so as to protrude from the bottle indicating to the deliverer the exact item 40 required.

Now having particular reference to the drawing my novel chart consists of a plurality of relatively narrow elongated cards 5 preferably of different colors and having marked thereon various items required as disclosed in Figure 1. At one end of said chart said cards 5 are loosely pivotally interconnected by a pivot pin 6, while extending from this pin at the center of the chart is an 50 eyelet member 7 so that the chart may be readily hung upon a nail or the like in the kitchen so that the chart will not become misplaced when not being used.

Arranged at the lower end of one of the

outermost cards 5 is an inwardly extending 55 spring clip 8 for facilitating the attachment of creamery tickets, a note of instruction or the like to the chart.

In actual practice the card bearing the particular item desired is swung directly rearwardly from its normal position with respect to the complete chart after which the chart is arranged within the milk bottle A, the particular card obviously projecting from the neck of the bottle for providing a particular 65 indicator to the deliverer that a certain item is desired.

In view of the foregoing description when considered in conjunction with the accompanying drawings it will be apparent that I 70 have provided a highly novel, simple and extremely useful ordering chart for creamery products and the like, even though I have herein shown and described the invention as consisting of certain detail structural elements it is nevertheless to be understood that some changes may be made therein without 75 affecting the spirit and scope of the appended claims.

Having thus described the invention, what 80 I claim as new and desire to secure by Letters Patent is:—

1. In an ordering chart of the character described, a plurality of similar elongated cards having particular items marked thereon, said chart adapted to be extended into a bottle, a loose pivotal connection between certain ends of the card whereby any one of the cards may be swung to a position longitudinally with respect to the chart for projecting beyond the neck of the bottle for indicating a particular order. 85 90

2. In an ordering chart of the character described, a plurality of similar elongated cards having particular items marked thereon, said chart adapted to be extended into a bottle, a loose pivotal connection between certain ends of the card whereby any one of the cards may be swung to a position longitudinally with respect to the chart for projecting beyond the neck of the bottle for indicating a particular order, and an eyelet member 95 extending longitudinally from the pivot connection whereby the chart may be suspended upon a hook. 100

3. In an ordering chart of the character described, a plurality of similar elongated cards having particular items marked there- 105

on, said chart adapted to be extended into a bottle, a loose pivotal connection between certain ends of the card whereby any one of the cards may be swung to a position longitudinally with respect to the chart for projecting beyond the neck of the bottle for indicating a particular order, and a spring clip

arranged upon one of the outermost cards and extending rearwardly with respect thereto whereby creamery tickets, notes or the like may be attached to said chart.

In testimony whereof I affix my signature.

THEODORE P. CORCORAN.
